The ornamental design for a round niche partition as shown and described.

DESCRIPTION

FIG. 1 is an upper perspective view of the round niche partition showing my design.

FIG. 2 is a front elevation view thereof;

FIG. 3 is a right side elevation view thereof;

FIG. 4 is a back elevation view thereof;

FIG. 5 is a left side elevation view thereof;

FIG. 6 is a top plan view thereof;

FIG. 7 is a bottom plan view thereof;

FIG. 8 is an exploded upper perspective view thereof; and,
FIG. 9 is another upper perspective view thereof, showing assembly with adjacent partitions in broken lines.

The round niche partition includes a symbolic break. The break lines form no part of the claimed design.

The portions in broken lines of FIG. 9 represent environment and form no part of the claimed design.
